UNITED STATES PATENT OFFICE.

EDWARD MORGAN AND CLEM D. BROWN, OF DAYTON, OHIO.

PISTON.

1,409,754.

Specification of Letters Patent. Patented Mar. 14, 1922.

Application filed February 26, 1920. Serial No. 361,502.

To all whom it may concern:

Be it known that we, EDWARD MORGAN and CLEM D. BROWN, citizens of the United States, residing at Dayton, in the county of 5 Montgomery and State of Ohio, have invented certain new and useful Improvements in Pistons, of which the following is a specification, reference being had therein to the accompanying drawing.

10 This invention relates to pistons for internal combustion engines and the like.

One object of the invention is to provide a piston of such a construction that it may be made entirely from steel, or similar metal, 15 at a relatively low cost.

A further object of the invention is to provide a piston in which the apron will be relieved of all strain and will be capable of uniform expansion, and in which the apron 20 may be made of relatively thin metal.

A further object of the invention is to provide a piston in which the cross head pin will be so mounted that it will be impossible for it to come in contact with the wall of 25 the cylinder.

A further object of the invention is to provide a piston comprising a plurality of separable parts, thereby facilitating the manufacture of the piston and enabling individual parts to be renewed when worn 30 without discarding the piston as a whole.

Other objects of the invention will appear as the device is described in detail.

In the accompanying drawings Fig. 1 is a 35 longitudinal sectional view taken centrally of the piston parallel with the axis of the cross head pin; Fig. 2 is a similar view taken transversely to the axis of the cross head pin; Fig. 3 is a transverse sectional view taken on the line 3—3 of Fig. 1 looking in the direction of the arrows; Fig. 4 40 is a perspective detail view of the apron; Fig. 5 is a perspective detail view of the piston head; and Fig. 6 is a perspective detail view of the yoke for the cross head pin.

In these drawings we have illustrated one embodiment of our invention and have shown the same as comprising a piston head 1 having an annular flange 2 extending rearwardly from the body portion thereof, which 50 in the present construction is in the form of a flat plate. This head may be formed in any suitable manner but we prefer that it be turned from a bar of steel and it is well adapted for production on an automatic 55 screw machine. The apron 3 is formed separately from the head 1 and is provided with a reduced portion 4 which fits snugly within the flange 2 of the head. Preferably this reduced portion of the apron is provided 60 with a flange 5 which rests upon the body portion of the head and provides a firm contact between the same and the apron. The apron is rigidly secured to the head in any suitable manner. As here shown, the apron 65 is provided with inwardly extending lugs 6 having therein apertures to receive studs 7 which project from the body portion of the piston head. In the present instance there are two of these studs and they are arranged 70 on a diametrically opposite side of the head. Any suitable means may be provided to retain the apron on the studs and in contact with the piston head. As here shown, the upper ends of the studs 7 are screw threaded 75 to receive nuts 8. The piston is provided with one or more annular grooves 9 to receive the usual piston rings, and in the present construction we have shown two such grooves formed in the flange of the piston 80 head.

The piston may be attached to the connecting rod, which is not here shown, in any suitable manner but we prefer to employ the usual cross head pin 10 and we have so mounted this pin that it will be supported independently of the apron, thereby relieving the apron of all strain, and further avoiding the necessity of forming bearings in the wall of the apron. Consequently, the 90 apron can be made of thin light stock and may be of a uniform thickness throughout its circumference, and will therefore expand and contract uniformly. The apron may be produced in various ways as by turning it from bar stock, but we prefer to draw the same from sheet steel, and if desired the rear end of the apron may be provided with an inwardly extending bead 11 to stiffen the same. As has been stated, the cross head 100 pin 10 is supported independently of the apron and to this end it is carried by the piston head. A supporting structure, or yoke, 12 is arranged within the apron and has an annular portion 13 which fits snugly 105 within the reduced portion of the apron and

rests upon the flange 5. This annular portion of the yoke is provided with inwardly extending apertured lugs 14 which embrace the stud 7 and are secured thereto by the 5 nuts 8. Extending rearwardly from the annular portion of the yoke are arms 15 having at their rear ends bearings 16 to receive the cross head pin 10. The cross head pin is secured in the bearings by suitable fastening means, such as pins 17, which, as here shown, are provided with screw threaded portions adapted to enter screw threaded apertures in the bearings.

The several parts of the piston are separately formed and then assembled to form 15 the complete piston. As has been stated we prefer to turn the head from bar steel and to draw the apron from sheet steel. The yoke may be a stamping, to which the bearings 20 are attached by welding, or other suitable means. It will be apparent therefore that the several parts can be produced in quantities at a very low cost and that they can be quickly and easily assembled. When 25 assembled they produce an all steel piston of light weight and of great strength, the cross head pin being mounted independently of the apron and no other parts being anchored thereto. Consequently, the apron 30 will expand and contract uniformly, maintaining its true cylindrical shape. The cross head pin is mounted wholly within the apron and consequently there is no possibility of its coming in contact with and scoring the 35 cylinder wall should it become loose in its bearings. Further, the cross head pin can not escape from its bearings even though the fastening devices should be omitted, because the pin is of such length that its longitudinal 40 movement in its bearings will cause one end thereof to come in contact with the apron before the other end has escaped from its bearing. Not only does this construction enable us to produce an all steel piston at a relatively low cost, but it also enables the individual parts of that 45 piston to be renewed when they become worn, thereby avoiding the necessity of discarding the piston as a whole because a 50 part thereof is worn out or injured.

While we have shown and described an embodiment of our invention we wish it to be understood that we do not desire to be limited to the details thereof as various 55 modifications may occur to a person skilled in the art.

Having now fully described our invention what we claim as new and desire to secure by Letters Patent is:

60 1. In a piston, a head having an annular flange, an apron separate from said head and having a reduced portion fitting snugly within said flange, said reduced portion having an inwardly extending part arranged 65 substantially parallel with said head, and

means for securing the inwardly extending part of said apron directly to said head.

2. In a piston, a head having an annular flange and having studs projecting therefrom within said flange, said head being provided exteriorly with piston ring grooves, an apron having a reduced portion fitting snugly within said flange and having apertured lugs to embrace the respective studs on 70 said head, and fastening devices cooperating with said studs to secure said apron to said head.

3. In a piston, a head having an annular flange, an apron having a reduced portion fitting snugly within said flange, and means 80 for attaching said apron to said head and for connecting said piston with a connecting rod independently of said apron.

4. In a piston, a head of rigid material having a circumferential flange projecting 85 from one face thereof and provided with piston ring grooves, an apron formed of sheet metal and having a reduced portion fitting snugly within said flange for the full depth thereof, and means for rigidly 90 securing said apron to said head.

5. In a piston, a head of rigid material having a circumferential flange projecting from one face thereof, and provided with piston ring grooves, an apron formed of 95 sheet metal and having a reduced portion fitting snugly within said flange for the full depth thereof, means for rigidly securing said apron to said head, a supporting structure arranged within said apron and rigidly 100 secured to said head independently of the lateral walls of said apron, and means carried by said supporting structure for connecting said piston with a connecting rod.

6. In a piston, a head having an annular 105 flange, an apron separate from said head and fitting snugly within said flange, and a yoke comprising an annular portion mounted within said apron and having arms provided with bearings, said apron and said 110 yoke being rigidly secured to said head.

7. In a piston, a head having an annular flange formed integral therewith, an apron formed separately from said head and having a portion to fit snugly within said flange, 115 a supporting structure for a connecting rod pin having a part to fit within said portion of said apron which lies within said flange, and means for securing said supporting structure and said apron to said head. 120

8. In a piston, a head having an annular flange, an apron having a reduced portion to fit within said flange, a yoke comprising an annular portion to fit within the reduced portion of said apron and having arms provided with bearings, and means for rigidly securing said yoke and said apron to said head.

9. In a piston, a head having an annular flange and provided with studs arranged 125

within said flange, an apron having a reduced portion to fit within said flange and having a portion provided with apertures to embrace said lugs, a yoke having an annular portion to fit within said reduced portion of said apron and having apertures to receive said studs and also having arms

provided with bearings, and fastening devices cooperating with said studs to secure said yoke and said apron to said head. 10

In testimony whereof, we affix our signatures hereto.

EDWARD MORGAN.
CLEM D. BROWN.
